UNITED STATES PATENT OFFICE.

HENRY E. STROHECKER, OF ENON, PENNSYLVANIA, ASSIGNOR TO CECIL F. ADAMSON,
OF EAST PALESTINE, OHIO.

ACCELERATOR FOR AUTOMOBILE-ENGINES.

1,097,566.

Specification of Letters Patent. Patented May 19, 1914.

Application filed February 21, 1914. Serial No. 820,306.

To all whom it may concern:

Be it known that I, HENRY E. STROHECKER, a citizen of the United States, residing at Enon, in the county of Lawrence and State of Pennsylvania, have invented certain new and useful Improvements in Accelerators for Automobile-Engines, of which the following is a specification.

My invention relates to accelerators for automobile engines, and is designed more particularly for use in connection with the engine of the well known Ford automobile, its primary object being to provide an accelerator which readily may be adapted to the Ford engine without the necessity of altering the latter, and without any change in the construction of the Ford automobile body.

These objects I accomplish in the manner and by the means hereinafter described and claimed, reference being had in the accompanying drawing, in which:

Figure 1, is a perspective view of my improved accelerator, the engine and car body being shown substantially diagrammatic. Fig. 2, is an enlarged detail sectional view taken through the pivot of the accelerator.

In the said drawing reference numeral 1 denotes an arm, having formed at its outer end a foot piece 2, and at its inner end being pinned or otherwise fixed to a vertical bearing rod 3. Said bearing rod 3 passes through an elongated sleeve 4, and at its lower end has pinned or otherwise fixed thereto a lever 5 which is bent downwardly and is at its lower end apertured at 6 and 7, for a purpose hereinafter to be described. The sleeve 4 is formed at its upper end with a lug 8 projecting horizontally to one side thereof, and coiled around said sleeve throughout its length is a spring 9, one end of which is engaged with the lever 5 and the other end with the lug 8, whereby when said lug is fixed the tension of said spring will be exerted on said lever 5 to move it laterally in one direction.

In applying my improved accelerator to a Ford car it is necessary only to remove one of the screws 10 used in the engine of said car to bolt together the cylinder casing, and to apply to said screw the lug 8 of my accelerator, which is suitably apertured to receive said screw. Upon replacing and screwing down said screw 10 the pivot of

the accelerator is in position for use. In thus positioning the device the foot piece 2 is first passed through a horizontal aperture 11 now found in dashboards of the Ford cars, thus obviating the necessity for any cutting to receive said foot treadle. The lever 5 at its lower end is connected with the valve of the carburetor by means of the usual rod 12 hooked into the aperture 6 in said lever, and is also connected with the usual throttle valve rod 13 of the car by means of a chain or other flexible connection 14.

The operation of the device when assembled will be obvious, it being observed that the pivot therefor is disposed vertically instead of horizontally, as is the case with other accelerators now in use. By this construction I am enabled to provide an accelerator which may be placed on the market complete as an article of manufacture, and which can be applied to the engine of the Ford car in particular without the necessity for any change either in the engine or in the car body. Furthermore said device when applied will not in any way interfere with the operation of the usual hand operated throttle lever now used in cars of this type.

Having thus described my invention, what I claim as new and desire to secure by Letters Patent is:—

1. An accelerator for automobile engines, comprising a horizontally shiftable foot treadle, a vertical pivot member comprising a rod and a sleeve to one of which said foot treadle is fixed, a bearing for said pivot member adapted to be supported by the engine casing, a lever also fixed to one of said pivot members and adapted to be connected at its free end with a carburetor valve, and a coiled spring encircling one of said pivot member parts and exerting its tension on said parts normally to maintain them in position to retain the carburetor valve closed.

2. An accelerator for automobile engines, comprising a horizontally shiftable foot treadle, a vertical pivot rod to which said foot treadle is fixed, a sleeve carrying said pivot rod, means for supporting said sleeve, a lever also fixed to said pivot rod and adapted to be connected at its free end with the carburetor valve, and a coiled spring carried by said sleeve and exerting its ten-

sion on said parts normally to maintain them in position to retain the carburetor valve closed.

3. An accelerator for automobile engines, comprising a horizontally shiftable foot treadle, a vertical pivot rod to which said foot treadle is fixed, a sleeve carrying said pivot rod, an apertured lug on said sleeve, a lever also fixed to said pivot rod and adapted to be connected at its free end with the carburetor valve, and a coiled spring disposed around said sleeve and at its end exerting its tension against said lever and said lug.
4. The combination with an engine casing and its bolts, of an accelerator comprising a horizontally shiftable foot treadle, a

vertical pivot rod to which said foot treadle is fixed, a sleeve carrying said pivot rod and adapted to be connected at its free end with the carburetor valve, a coiled spring disposed around said sleeve and exerting its tension on said lever, and a lug on said sleeve adapted to engage one of the bolts of the engine casing to maintain said foot treadle, pivot rod and lever in operative position.

In testimony whereof I have hereunto set my hand in the presence of two subscribing witnesses.

HENRY E. STROHECKER.
